A. D. T. Libby
ATTORNEY

UNITED STATES PATENT OFFICE.

THOMAS G. MEINEMA, OF CHICAGO, ILLINOIS, ASSIGNOR TO THE HOLTZER-CABOT ELECTRIC CO., OF CHICAGO, ILLINOIS.

TELEPHONE TONE MACHINE.

Application filed March 5, 1927. Serial No. 172,982.

This invention is a continuation in part of my previously filed application Serial No. 17,014, filed March 20th, 1925, for a telephone tone machine, and relates to an apparatus or machine for furnishing tone currents for use in a telephone exchange system. In a telephone exchange tone currents are used for various purposes. For example there is a "busy back" and "don't answer", dial tone, trouble tone, howler tone, and tones for cable testing the latter being usually referred to as tone test current. These various audible tones or signals may be thus transmitted to a subscriber, or an inspector or lineman using or testing the telephone line.

Heretofore, it has been the custom to provide preferably, on the end of the shaft of the ringing machine, that is the machine which is used for supplying current for ringing the telephone bells, a commutator consisting of quite a number of segments and feeding the exchange battery current through this high frequency commutator, and then through a relatively high winding of an induction coil which has an additional relatively low resistance winding having one end connected to the exchange battery and the other to a slow speed commutator, ordinarily referred to as the busy-back and don't answer interrupters; the busy-back interrupter being connected to a series of jacks usually on the trunk board of the telephone exchange, while the don't answer interrupter is connected to another series of jacks on the same board, as diagrammatically illustrated in Dean Patent 818,527 of April 24, 1906.

In the past, a connection is sometimes taken from the same induction coil winding, used in connection with the busy-back and don't answer interrupters, directly through a suitable test plug or switch, which may be installed at the wire chief's desk, or at any other suitable place, such a connection being known as the tone test circuit, which is usually used when a line is in trouble, and it is desired to put a tone on the sleeve of the jack of the line that is in trouble, to notify any operator in testing the jack, to see if the line is busy, that the line is in trouble.

In order to obtain a much stronger current for the howler tone, which is used for making a subscriber replace his receiver on the hook, when it is inadvertently not re-

turned thereto, or has become accidentally pushed off the hook, thereby giving a signal to the operator, it has been the past practice to use an induction coil separate from the busy-back and don't answer coil, the primary of this coil being connected to a high speed interrupter and the secondary carried to any suitable switching point, whereby the howler current may be connected to the subscriber's line.

Where these tone currents are controlled by the high frequency interrupters previously referred to, much trouble has been encountered, in that the brushes, particularly on the high frequency interrupters are apt to be worn out, and the collector rings or commutators get dirty, and become pitted from wear and sparking at the brushes, thereby necessitating sandpapering the commutators very frequently in order to keep the quality of the tone somewhere near a uniform scale.

It is therefore the principal object of my invention to provide a machine in which the various tone currents heretofore referred to are produced without the use of brushes, collector rings, or commutators, and at the same time to provide a machine in which the tone currents generated are steady and uniform.

Another object of my invention is to provide a combination in which separate induction coils are not required, thereby simplifying the wiring of the entire combination.

These and other objects will be apparent to one skilled in this art, after a study of the specification taken in connection with the annexed drawing, wherein

Figure 1 is a somewhat diagrammatic view of one half of my inductor tone machine.

Figure 2 is a view similar to Figure 1 but showing a machine capable of generating a higher frequency tone current.

Figure 3 is a partial vertical section through either Figures 1 or 2.

Figure 4 is a fragmentary view of a modified form of construction showing three windings instead of two as shown in Figure 3.

Figure 5 is a further modified form of tone machine showing a plurality of means for generating tone currents of the same or different frequencies.

Figure 6 is a diagrammatic view illustrating how the induction machine is con-

nected to the telephone exchange system, the windings of the inductor only being shown.

Referring now to the details, wherein like numbers refer to corresponding parts in the various views, 1 illustrates a stator or non-rotating part of a machine which is preferably built up of laminations of suitable quality of magnetic material, the laminations being shown particularly in Figure 3. The stator 1 is provided with a series of pole pieces 2 and 3, which are arranged in pairs spaced apart as shown more clearly in Fig. 3. Between the series of spaced pole pieces 2 and 3, a pair of annular concentrically arranged windings 4 and 5 are provided and the winding 4 is of considerably higher resistance and usually of greater number of turns, than the winding 5. The winding 4 is connected across the exchange battery "B" and is thus used as an exciting winding. Winding 5 has one end preferably connected to the negative side of the exchange battery "B" while the other end 6 is connected to a brush 7 operating on a ring 8 of a slow speed interrupter. The ring 8 is connected to a series of segments 9 of a busy-back commutator 10 which is wired through the brush 11 to a series of busy-back jacks 12 at the switchboard, only one of these jacks being shown. The ring 8 is also connected to a series of segments 13 of a don't answer commutator 14 on which the brush 15 operates and this brush is connected to a series of don't answer jacks 16 at the switchboard, as shown in the said Dean patent previously referred to, resistance coils 29 and 30 being used in connection with the busy-back and don't answer jacks 12 and 16. A tap 17 is taken from the end 6 of the winding 5 to a switch 18 marked also T. T. S. signifying "tone test switch", which may be located at any desired point in the exchange. The slow speed interrupters are preferably connected to the shaft 19 of the machine through a reducing gear of the proper kind.

While I have shown a certain type of slow speed interrupter I may also use and preferably do use interrupters composed of spring contacts operated by cams, but since this feature is no part of my present invention the older form of interrupter is shown.

The shaft 19 carries a rotor 20, having a series of pole pieces 21 to cooperate with the pole pieces 2 and 3 of the stator, thereby varying the flux through the windings so that a tone is imparted to the winding 5, which tone may be picked up directly through the switching device connected to a tap or wire 17, for the tone test current as described. The terminal 6 of the coil 5, is also connected by a brush or contact 7, to the busy-back and don't answer interrupters as described.

The howler current may be obtained in a plurality of ways, one in particular, being shown in Figures 4 and 6, wherein the winding 22 is such that the howler current is taken direct from the terminal 28 of the coil 22 to the (H. S.) howler switch and in order to vary the strength of this howler tone current I provide taps 25 and 26 to which the connection 28 may be switched if desired. I also provide the winding 5 with taps 23 and 24 to which the ends 6 of the wire 17 may be connected.

The tone test current may be picked up between the points 25 and 27 without the use of the winding 5 leaving the howler current to be taken from the extreme end of the winding 22 or an adjacent tap such as 26. When this construction is used I prefer to make that portion of the winding 22 between the points 27 and 25 of lower resistance than the remainder of the winding 22. When this latter arrangement is used then two windings such as shown in Figures 3 and 5 may be all that is required to provide the necessary tone currents to the exchange.

In some cases in a relatively large exchange where the requirements are greater, tone currents of different frequencies are used and to obtain them a construction such as illustrated on the Figures 1 and 2 may be utilized in one machine as shown in Figure 5. The windings 4 and 5 may be used in the manner already described, or each tone unit may have three windings, as shown in Figure 4. In addition the tone units included within the housing 31 of a single machine may be constructed to have the same frequency according to Figure 1, or Figure 2.

From what has been said it will be readily understood that the drawing is merely illustrative of my invention, the details of which may be varied over a considerable range without departing from the spirit of the invention and the scope of the appended claims.

Having thus described my invention, what I claim is:

1. A tone machine for a telephone switchboard system comprising a stator having a plurality of poles, an exciting winding therefor, at least one tone winding having one end connected to the system battery and the other end leading to a suitable switching point including a subdividing signal apparatus and a rotary inductor cooperating with said stator pole pieces to produce magnetic flux changes therein whereby a tone current is set up in said tone winding.

2. A tone machine for a telephone switchboard system comprising a stator having a plurality of poles, an exciting winding therefor, connected to the system battery, at least one tone winding having one end connected to the negative end of the system battery and the other end connected at least to a sub-

dividing signaling device interposed between the tone machine and a switching point and a rotary inductor cooperating with said stator pole pieces to produce magnetic flux changes therein whereby a tone current is set up in said tone winding.

3. A tone machine for a telephone switchboard system comprising a stator having a plurality of poles, a single coil exciting winding energized by the telephone system battery at least a single coil tone winding adjacent said exciting winding adapted to have the system battery current fed therethrough, one end of said tone winding being connected at least to a subdividing signaling device interposed between the tone machine and a switching device and a rotary inductor cooperating with said stator pole pieces to produce magnetic flux changes therein whereby a tone current is set up in said tone winding.

4. A tone machine for a telephone switchboard system comprising a stator having a plurality of poles, at least a single coil exciting winding of relatively high resistance energized by the system battery, a single coil tone winding of relatively low resistance adjacent said exciting winding and adapted to have the system battery current fed therethrough one end of said tone winding being connected at least to a subdividing signaling device interposed between the tone machine and a switching device and a rotary inductor cooperating with said stator pole pieces to produce magnetic flux changes therein whereby a tone current is set up in said tone winding.

5. A tone machine for a telephone switchboard system comprising a stator having a plurality of poles arranged in pairs spaced apart around the inner periphery of the stator, at least a pair of coils concentrically arranged with respect to each other within the annular space between said spaced apart pole pieces, one of said coils being excited from the system battery and another coil being connected to one end of the system battery while the other end is connected to a tone selecting device associated with the tone machine and a rotary inductor having poles to cooperate with said stator poles to produce a tone current in the second mentioned winding.

6. A tone machine for a telephone switchboard system comprising a stator having a plurality of poles, an exciting winding therefore, at least a second winding associated with the exciting winding and adapted to have the system battery current passed therethrough to a tone separator and signalling device having leads adapted to be connected to various switching devices of the switchboard system and a rotor having inductors capable of altering the magnetic flux through said second winding whereby a tone

current is set up therein for the purposes described.

7. A howler and auxiliary tone and signalling machine for a telephone system comprising, a stator, a rotor, an exciting winding for the stator, a howler winding associated with the exciting winding and adapted to have the system battery current passed therethrough to the auxiliary tone and signalling device operated by said rotor and thence to the telephone switchboard as and for the purpose described.

8. A tone machine for a telephone switchboard system comprising; a stator having a plurality of poles, means for setting up magnetic flux in said poles, at least one stationary winding associated with said poles, and having circuit connections with switching devices of the switchboard system and a rotor having inductors capable of altering the magnetic flux through said winding whereby a high pitched tone current is set up therein.

9. A composite tone machine for a telephone switchboard system comprising; a stator having a plurality of poles, means for setting up magnetic flux in said poles, at least one tone winding associated with said poles, means for selecting from said winding, tone currents of different effective strength and circuit connections leading said tone currents to switching devices of the switchboard system and a rotor having inductors capable of altering the magnetic flux through said winding whereby said tone currents are set up therein.

10. A composite tone and signalling machine for a telephone switchboard system comprising; a stator, a rotor, an exciting winding for the stator and means for energizing the same, at least one tone winding associated with the exciting winding and means for supplying current thereto said winding being provided with taps whereby tone currents for different purposes may be taken therefrom, one of said taps being taken to a signalling device operated by said rotor and thence to the telephone switchboard for the purpose described.

11. A composite tone and signalling machine for a telephone switchboard system comprising; a stator, a rotor an exciting winding for the stator and means for energizing the same, a plurality of tone windings associated with the exciting winding and adapted to have the system battery current passed therethrough, one of said tone windings having connections leading direct to switching devices of the system while another of said tone windings is adapted to be connected to signalling devices operated by said rotor and thence to the telephone switchboard for the purposes described.

12. A composite tone machine for a telephone switchboard system comprising; a

- 4
- stator having a plurality of poles, means for setting up magnetic flux in said poles, at least one tone winding associated with said poles, a separate source of current adapted to be passed through the tone winding, means for selecting from said winding, tone currents of different effective strength and circuit connections leading said tone currents to switching devices of the switchboard system and a rotor having inductors capable of altering the magnetic flux through said winding whereby said tone currents are set up therein.
13. A composite machine for a telephone switchboard system for delivering uniform tone currents of different frequency and of a desired strength comprising; a plurality of closely arranged stators each having a plurality of poles but differing in number, an exciting winding for each stator and means for energizing the same, at least one stationary tone winding arranged adjacent each exciting winding and adapted to be connected to switching devices of the said system and closely arranged rotors one for each stator having inductors capable of altering the magnetic flux through said tone windings whereby the tone currents are set up therein.
14. A composite machine for a telephone switchboard system for delivering uniform tone currents of different frequency and of a desired strength comprising; a plurality of adjacently arranged stators each having a plurality of poles but differing in number, an exciting winding for each stator, and adapted to be excited from the system battery, at least one tone winding arranged adjacent each exciting winding and connected at one end to the system battery, while the opposite end is adapted to be connected to switching devices of the said system, and a plurality of rotors, corresponding to the number of stators, arranged adjacent each other on a common shaft and having inductors capable of altering the magnetic flux through said tone windings whereby the tone currents are set up therein.
15. A composite machine for a telephone switchboard system for delivering a plurality of tone currents each of a desired strength comprising; a plurality of closely arranged stators each having a plurality of poles, means for setting up magnetic flux in said poles, at least one stationary tone winding associated with each of said stators and adapted to be connected to switching devices of the said system and closely arranged rotors, one for each stator having inductors capable of altering the magnetic flux through said tone windings whereby the tone currents are set up therein.

In testimony whereof, I affix my signature.

THOMAS G. MEINEMA.
